CARTON FOR AN AUTOMOTIVE AIR FILTER

Robert J. Offer and Eugene J. Samalon, Racine, Wis., assignors to Tenneco Inc., Racine, Wis., a corporation of Delaware

Filed Jan. 9, 1970, Ser. No. 20,854

Term of patent 14 years

Int. Cl. D9—06

U.S. Cl. D9—250

FIG. 1 is a perspective view of a carton for an automotive air filter showing our new design;

FIG. 2 is an end elevational view; and

FIG. 3 is a side elevational view partially broken away.

We claim:

The ornamental design for a carton for an automotive air filter, substantially as shown.
